UNITED STATES PATENT OFFICE.

REUBEN LEZOTT, OF PLATTSBURG, NEW YORK.

IMPROVEMENT IN RAILROAD-SWITCHES.

Specification forming part of Letters Patent No. 44,537, dated October 4, 1864.

To all whom it may concern:

Be it known that I, REUBEN LEZOTT, of Plattsburg, Clinton county, and State of New York, have invented new and useful Improvements in Railroad-Switches; and I do hereby declare that the following is a full and exact description of the same, reference being had to the accompanying drawings, and to the letters of reference marked thereon, making a part of this specification.

The nature of my invention consists in the shape and construction of movable and adjustable heads to fit the rails and operate as an economical and adjustable switch for sidings of railway-tracks.

Figure 1 represents the movable heads. Fig. 2 shows the mode of attaching the heads to the rails; Fig. 3, a switch formed of a series of heads attached to a siding.

A represents the common T rail of railways, with its flange B on each side forming the base.

C represents the iron horizontal connecting-rod as commonly attached to railway-switches. I make notches upon the upper side of this rod.

E are iron heads that are movable. They are

made rounding, with a projecting flange, G, at top to fit upon the top side of the flange B of the rail. These heads form jaws that clasp the rails on each side. They also have a hole through their center, through which the rod C is passed, and a hole through their sides, in which pins or bolts H are driven, the bolts fitting into the notches D, so as to permanently fasten the heads E to the rod C and be firmly attached to the rail. The object and advantage are, that in case of a head, E, breaking (as often happens) a new one is immediately attached to the rod, thus saving much labor, time, and expense in replacing a head; also, the width of the track can be more easily altered to any required distance by adjusting the heads and making the width of the switch to suit the track or siding.

What I claim as my invention, and desire to secure by Letters Patent, is—

The movable heads as attached to the horizontal rod, as herein described, and for the purposes set forth.

REUBEN LEZOTT.
